ELECTRICAL CORD EXTENSION DEVICE

John W. Johnson, St. Maries, Idaho

Application February 11, 1936, Serial No. 63,387

2 Claims. (Cl. 173—367)

My present invention relates to improvements in electrical cord extension devices of the portable type, and the invention especially involves the utilization of a pair of independently operated, 5 spring-actuated drums or reels, turnable with relation to each other and in opposite directions. In carrying out my invention I provide an automatically operating take-up device which controls two cords or electric cables, one extending from 10 the wall socket or plug connection to the extension device, and the other cord extending from the extension device to the electrical appliance, as for instance, an electrically heated iron.

The extension device is portable and it is 15 equipped with attaching means whereby the device may with facility and convenience be attached to the edge of a table or to the edge of an ironing board in desired position for use, and the device may with equal facility quickly be detached when 20 not required for use.

The extension device is adapted for various uses, as for instance with electrically heated coffee percolators, toasters, etc., and it is particularly desirable for use on ironing boards to take up slack in 25 the cord as the iron is being moved back and forth during the operations of ironing.

Electrical connections are provided whereby a 30 continuous and constant electrical connection is maintained between the wall socket or outlet plug and the electrical appliance being used, and the usual control switch or switches are employed in combination with the device.

In some instances the invention may be embodied in a non-portable, or stationary device, as a 35 wall-fixture, from which either, or both of the cords may be withdrawn, and automatically retracted, thus permitting the electrical appliance to which a cord is connected, to be moved to desired position, and yet maintain the cord in taut or unslacked condition.

In the accompanying drawings I have illustrated two examples of the physical embodiment 40 of my invention, wherein parts are combined and arranged according to the best modes I have thus far devised for the practical application of the principles of my invention, but it will be understood that various changes and alterations may be made in these exemplifying structures within the scope of my claims, without departing from the 45 principles of my invention.

Figure 1 is a perspective view of the portable extension device illustrating the manner of attaching it to a table edge or an ironing board.

Figure 2 is a vertical sectional view of the device, as at line 2—2 of Figure 3.

Figure 3 is a transverse vertical sectional view of the device as at line 3—3 of Figure 2.

Figure 4 is a transverse sectional detail view of one of the reels or drums, as at line 4—4 of Figure 3.

Figure 5 is a fragmentary perspective view showing in detail one of the electrical connections between two reels or drums.

Figure 6 is a horizontal sectional view at line 6—6 of Figure 7 of a non-portable device, or a 10 wall fixture.

Figure 7 is a side elevation of a wall fixture embodying my invention, and Figure 8 is a perspective view of the face plate for the wall fixture.

Figure 9 is a sectional view with parts in dotted 15 lines showing the electrical connections, including the house-wiring for the wall fixture.

In Figure 1, where the extension device is shown attached to the edge of an ironing board B, the operating parts are enclosed within a housing H, and the housing is provided with a clamp 1, pivoted in bearings 2 on the brackets 3 that are rigid with the housing, and a spring 4 is interposed between the clamp and a handle H' of the housing. Thus, with the thumb on the handle H' and the finger beneath the rear end of the clamp 1, the latter may be spread to slip under the board B, and when the thumb and finger are released, the clamp 1 firmly holds the device in position for use.

The cords 5 and 6 are preferably of the flat, rubber covered type, enclosing two wires, and the cord 5 is equipped with a conventional type of plug or connector P for attachment to an outlet or wall-socket. Cord 5 enters the housing through a slot S and the cord 6, which extends to the electrical appliance, as for instance, an electrically heated iron, also enters the housing H through a similar slot S.

Cord 5 is wound upon a rotary reel 7, which is 40 loosely mounted upon a shaft 8, and a spring 9 enclosed within the central hollow hub portion of the reel, has one end attached to the reel and its other end attached to the shaft, in order that the cord 5 may automatically be wound, by the 45 spring, on the reel in anti-clockwise manner.

Cord 6, extending to the iron, is automatically wound, clockwise on the reel 10 by the spring 11, the ends of the spring being attached to the reel and the shaft 8 to accomplish this purpose.

The two wires of each cord 5 and 6 are attached, each pair, to a terminal block as 12 on reel 7 and 13 on reel 10, and these blocks are inset in the reels and fastened thereto, not only for the purpose of anchoring or attaching the 55

cords, but also for distribution of the electrical currents in the wires of the cords.

The shaft 8, on which the reels are mounted through the instrumentality of their springs, is 5 mounted in bearing supports 14 of the frame 15, and the frame is enclosed within the housing H and secured firmly thereto by screws as 15a. Thus, the housing forms a removable part of the device to enclose the operating parts and to 10 guide the cords as they are wound or unwound, and the frame also has an arcuate shaped guide plate 14a adjacent to the lower portion of the reels for guiding the cords, and preventing them from being displaced.

15 Electrical connection is provided between the cord 5 and the cord 6, and the two reels, through the use of two annular conductors or rings 16 and 17, one annular conductor being attached to each of the inner or adjoining, exterior faces of 20 the reels, and these rings are electrically connected at 18 to their respective terminals 12 and 13. Each reel also has a brush as 19 and 20 mounted thereon to contact with the annular conductor on an adjoining reel, and these brushes 25 are each mounted at the free end of a spring blade 21 that is fastened by a screw 22 to the inner face of the reel, and a connection at 23 is made from a brush to a terminal on the terminal block. The spring blades hold the brushes in 30 contact at all times with the conductor rings, and to permit freedom of movement and avoiding interference between the brushes as they rotate in opposite directions with their respective reels, the brushes are arranged as indicated by full lines 35 and dotted lines in Figure 2. In Figure 2 it will be noted that one brush is mounted on a blade located within the circle or circumference of the conductor rings and the other brush is mounted on a blade located outside of the circumference 40 of the conductor rings.

In the wall fixture, or stationary extension device of Figures 6, 7, 8, and 9, the frame 15 is attached at the inner side of the wall W, and the cords 5 and 6 pass through slots S' in the outer face plate 23', to the reels 7 and 10 that are 45 mounted on the shaft 8. The house wire to supply electrical current to the cords and to the appliances to which the cords are connected, is connected to the device at 24 and 25, and these terminal wires 24 and 25, are each connected to a brush as 26 and 27. These brushes 26 and 27 are located at the exterior sides of the two reels, and the brushes frictionally and electrically contact with conductor rings 28 and 29 respec-

tively mounted on the exterior faces of the reels. In the diagrammatic showing of Figure 9, the two exterior conductor rings 28 and 29 are connected at 30 and 31 to the terminals 12 and 13 of the reels, and the reels are electrically connected to 5 each other, and to their respective cords, as previously described.

The stationary extension device is rigidly attached, as by screws 32 to the wall plate W, and the reels automatically turn in opposite directions to re-wind the cords 5 and 6. One of the cords 5 and 6 may be used singly to supply current to an electrically operated appliance to which the cord is connected, or both of these cords may be employed simultaneously to supply 15 current to the appliances to which the cords are attached, and of course the cords may be extended or contracted at will.

In the portable extension device, where the housing H may readily be removed by withdrawing the screws 15a, the shaft is mounted in the frame so that the reels may readily be detached from the supporting frame, after the housing has been removed. To permit ready removal of the reels from their supporting frame, the shaft 8, 25 which is tubular, has its ends journaled in bearings 14 of the frame members 15, and near these ends are arranged pairs of diametrically arranged holes 33 for the reception of cotter pins 30 located outside the frame members 15.

Having thus fully described my invention, what I claim as new and desire to secure by Letters Patent is:—

1. In an extension-device for electric-cords, the combination with a pair of spaced oppositely 35 rotatable, spring-wound, opposed reels each having a conductor ring, of a spring blade mounted on each reel, and a brush mounted on each blade and each brush frictionally engaging the conductor ring on the opposite reel.

2. In an extension device for electric cords, the combination with a pair of spaced, coaxially mounted, oppositely rotatable, spring-wound reels each having a conductor ring mounted on its face adjoining the face of the other reel, of a 45 spring-blade having its inner end fixed to one reel within the inner circumference of said rings, a brush on the free end of said blade engaging the ring of the other reel, a second spring-blade, having its inner end fixed to said other reel outside the periphery of said rings, and a brush on the second blade engaging the ring on the first reel.

JOHN W. JOHNSON.
